UNITED STATES PATENT OFFICE

154,442

DESIGN FOR A VEHICLE WHEEL SPINNER

Frederick T. Towne, Dallas, Tex., assignor to
Service Sales Company, Inc., Dallas, Tex.

Application January 16, 1948, Serial No. 143,828

Term of patent 7 years

(Cl. D52—1)

To all whom it may concern:

Be it known that I, Frederick T. Towne, a citizen of the United States, residing at Dallas, in the county of Dallas and State of Texas, have invented a new, original and ornamental Design for Vehicle Wheel Spinner, as shown, of which the following is a specification, reference being had to the accompanying drawing, forming part thereof.

Figure 1 is a left front perspective view of a vehicle wheel spinner, showing my new design.

Figure 2 is a right front perspective view.

Figure 3 is a top plan view, and

Figure 4 is a rear elevational view thereof.

I claim:

The ornamental design for a vehicle wheel spinner, substantially as shown.

FREDERICK T. TOWNE.
